LYMAN R. ROBERTS, OF DETROIT, MICHIGAN, ASSIGNOR TO UNDERWOOD
TYPEWRITER COMPANY, OF NEW YORK, N. Y., A CORPORATION OF NEW
JERSEY.

TYPE-WRITING MACHINE.

No. 853,266.

Specification of Letters Patent.

Patented May 14, 1907.

Application filed September 29, 1905. Serial No. 280,667.

To all whom it may concern:

Be it known that I, LYMAN R. ROBERTS, a citizen of the United States, residing in Detroit, in the county of Wayne and State of Michigan, have invented certain new and useful Improvements in Type-Writing Machines, of which the following is a specification.

This invention relates to the type actions of writing machines, and particularly those of the visible writing class, in which the type bars are assembled compactly on one side of the printing point.

One object of the invention is to provide long pivot bearings for the type bars, and to this end I use short and long type bars; the short ones pivoted in an arc which is immediately within the arc in which the long bars are pivoted; and instead of having the type ends of the bars in staggering arrangement as usual where alternate short and long bars are employed, I contrive to have the types lie in an even row, as usual in front strike writing machines in which the bars are of uniform length, and thereby the types are brought within the smallest possible compass. I provide individual hangers for the type bars, with improved means for adjusting the hangers and type bars. The hangers are in the form of strips folded to receive the type bar hubs, and provision is made for taking up the play of the pivots, and also for strengthening the hanger at the pivot end.

A further object is to avoid offsetting the types laterally from the main arms of the type bars to such an extent as is customary in front strike writing machines. To this end, in place of the customary double type made in one piece, I employ individual shank types, one for each character, and in each types bar I provide two or more sockets to receive these types. The bar extends directly, or without lateral bending, from its pivot to the socket of the first type, and is bent laterally between the types so as to enable the types on all the bars (which are grouped radially to the printing point) to print in the same place.

A further object of the invention is to improve the touch upon the keys, and to this end I employ sub-levers between the key levers and type bars, and give the key levers bearings directly upon the sub-levers at points remote from the fulcrums of the latter so as

to give an easy start to the keys; and I also extend links from the key levers to the sub-levers which are idle during the first parts of the type strokes, but at the latter parts of said strokes engage the sub-levers at points near the fulcrums of the latter, thereby speeding the type bars to make the impressions and tending to relieve the shock upon the fingers of the operator as the keys are arrested. Further objects and advantages will hereinafter appear.

In the accompanying drawings, Figure 1 is a sectional elevation taken from front to rear of the type action of a front strike writing machine made in accordance with my improvements. Fig. 2 is a front view of an improved segment upon which the type bars are mounted. Fig. 3 is a plan of the type bars detached from their hangers, only the type bars of the left hand half of the system being shown. Fig. 4 is a perspective view of the type bar and hanger, the latter broken away to illustrate the pivotal adjustment.

Upon the front side of a platen 1 strike lower case and upper case types 2 and 3, having shanks inserted in sockets 4 and 5 of short and long type-bars 6 and 7, which are radially disposed to the printing point. The pivots 8 of the short type bars lie in an arc below the platen and immediately within or above the arc in which lie the pivots 9 of the long type bars. As illustrated, the type bars swing through about 90 degrees from normal position to the printing point. An imaginary line 10 drawn through the pivots 8 and 9 at Fig. 1 would form an angle of about 45 degrees to a vertical plane parallel with the front of the platen where the types strike. The types 2 on both the long and short type bars, although moving in different arcs, still lie evenly side by side in the type basket, the same as if the type bars were all of one length, since the pivots 9 are in such relation to the pivots 8 that the arcs 11 and 12 coincide where they touch the types in normal position. It will be understood that if the types move through either more or less than 90 degrees, the line 10 may be shifted accordingly, so that it shall form an angle with said vertical plane (designated as 13) equal to about half the angle through which the type bar swings. Said plane 13 may form the base of a right cone having its axis 14 coincident with the printing point, and its sides

10 forming an angle of 45 degrees more or less with the base; and it will be seen that the pivots 9 lie at the junction of the base and sides of said cone, while the pivots 8 lie in the sides of the cone. At Fig. 3, which shows the type bars as they would appear if developed from their actual circular arrangement to a position in which their pivots would be all horizontal, it will be seen that the types form a substantially even row, as distinguished from the staggering arrangement of types usual where alternating long and short bars are employed; the pivots of the lower arc being sufficiently far in rear of the pivots in the upper arc to effect this result.

The type bars are mounted in individual hangers 15 and 16, the former adjustable forwardly and backwardly upon the inner or upper cylindrical face 17 of a segment 18, and held where adjusted by screws 19, and the latter adjustably secured by screws 20 upon a conical outer or lower face 21 of said segment; the face 21 being parallel with 10, so that the hanger 16 may be adjusted obliquely thereon in a direction to carry the pivot 9 along the line 10 directly to or from the pivot 8, whereby the types on the long bar 7 may be adjusted to strike accurately at the printing point without throwing them appreciably out of line with the types of the short type bars. Moreover, it will be seen that the hangers 16 may be adjusted forwardly and backwardly so as to bring their types when in normal position in aline with the types on the long type bars, without appreciably varying the printing positions of the types on the short type bars. Hence all the types may be properly alined both in printing and normal positions, notwithstanding the use of alternately long and short type bars. Any hanger may be removed by simply unscrewing its screw 19 or 20, and another hanger and type-bar substituted, as will be understood.

It will be seen that the hangers 15 and 16 are formed of strips of sheet metal folded to form loops to receive the screws 19 and 20, said loops rigidly secured near their free ends by rivets 22, which clamp the sides of the loops against interposed blocks 23. The tips of the hangers are thus enabled to support rigidly the type bars, so that the latter are carried true to the printing point. The pivots 8 and 9 of the type bars are in the form of coned gudgeons, which have bearings in screws 24, threaded into holes 25; in the hangers the screws being axially perforated and coned to receive said gudgeons.

The hangers 16 are entirely clear of the hangers 15; the bars 7 vibrating up between the adjoining hangers 15. All of the hangers may be sufficiently wide to enable the employment of such long pivots upon the type bars that accuracy of printing is in-

sured; the hangers in one arc or tier overlapping those in the other, as will be understood from Fig. 3.

At Fig. 3 it will be seen that the pairs of types 2 and 3 lie at various angles to the type bars and that the latter are bent at about the point 26 between the types or type sockets 27 and 28. The type bars extend directly or straight at Fig. 3 between their pivots and the nearest types 2, these being the lower case types and most frequently used, so that when types 2 are printed there is no lateral or torsional strain upon the type bars and hence good impressions are secured without having the type bars unduly heavy. The necessary lateral bends or crooks in the type bars are very short, as seen at Fig. 3, so that the upper case types 3 are not unduly offset from the type bars. By having individual types instead of the usual double types, the bend or crook can be made at the point 26 (at the junction of the crook with the body of the bar), or between the types, which is impracticable where double types are employed.

The type bars are operated by keys 29 mounted upon the front ends of levers 30 of the second order, extending rearwardly beneath the type bars and having between their ends upwardly extending arms 31 provided at their tips with lateral pins or projections 32 which bear directly upon suitably curved edges 33 of bell-cranks 34 having fulcrums at 35. Upwardly extending arms 36 of said bell cranks are connected by adjustable links 37 with short arms 38 formed upon the under side of the type bars and suitably hooked to clear the hanger blocks 23. It will be seen at Fig. 1 that the bearing pins 32 are quite remote from the bell-crank fulcrums 35, whereby the type bars are easily started in motion. Just in rear of said upwardly extending arms 31, I connect to the key levers adjustable links 39, which extend up to the bell-cranks 34 and are loosely connected to the latter between the pins 32 and the fulcrums 35. The upper end of each link is hooked at 40 to catch within a slot 41 formed in the bell-crank, whereby during the initial portion of the movement of the latter, said link is idle. During the last part of the type stroke, however, the link is effective and acts upon the bell-crank at a relatively small leverage in comparison with the pin 32, as will be understood from the parts seen in printing position at Fig. 1. The parts are returned to normal position by springs 42 connected to the upper ends of the bell-crank arms 36 and extending rearwardly over the links 37 and connected to the type bars at 43 between the pivots of the latter and the points of connection of said links; the latter being connected to said arms 36 between said springs and the fulcrums 35. Said springs are consequently distended during the printing strokes of the

type bars so as to be effective to return the same to normal position.

In the form of my invention shown at Fig. 1, if the springs 42 are cast off, the type bars immediately rise to the printing point, thus showing that very little resistance beyond the tension of said springs has to be overcome by the operator in manipulating the keys, so that fatigue is avoided and speed of operation is assured.

Having thus described my invention, I claim:

1. In a typewriting machine having a platen, a system of type bars pivoted to swing against the front side of the platen and each carrying a pair of types; the type bars pivoted in two arcs one immediately above the other, the type bars pivoted in the lower arc being longer than the type bars pivoted in the upper arc, and the upper type-bar pivots lying in the sides and the lower type-bar pivots at the junction of the sides and base of a cone whose axis substantially coincides with the printing point on the platen; the type bars pivoted in the lower arc being mounted upon individual hangers which are mounted upon a conical segment of such form that the hangers may be adjusted thereon so as to carry their type-bar pivots directly toward the pivotal axes of the type bars pivoted in the upper arc.

2. In a typewriting machine having a platen, a system of type bars pivoted to swing against the front side of the platen and each carrying a pair of types, the type bars pivoted in two arcs one immediately above the other, the type bars in the lower arc being longer than the type bars in the upper arc, the upper type-bar pivots lying in the sides and the lower type-bar pivots at the junction of the sides and base of a cone whose axis substantially coincides with the printing point on the platen; the type bars pivoted in the lower arc being mounted upon individual hangers which are mounted upon a conical segment of form to permit the adjustment thereon of the lower hangers directly toward the pivotal axes of the upper type bars; and the hangers of the upper arc being adjustable forwardly and backwardly upon said segment.

3. In a typewriting machine, a system of alternating long and short pivoted type bars, the type ends of the long bars lying in substantial alinement with the type ends of the short type bars when in normal positions, and each type-bar carrying a plurality of types, the types lying at various angles to the type bars, individual overlapping hangers for said type bars, and a segment having a conical surface whereon the hangers for the long type bars are mounted for adjustment toward and from the apex of the cone.

4. In a front strike writing machine having a platen, the combination of a system of

rearwardly striking alternating short and long pivoted type bars, the long type bars pivoted below and a little in rear of the short type bars, the type ends of the long bars substantially alining with the type ends of the short type bars when in normal positions, each type bar carrying a plurality of types, all of said type bars provided with hangers, and a segment whereon said hangers are individually adjustable, the hangers for the short type bars mounted upon the upper side of said segment, and the lower side of said segment having a conical form and bearing the hangers for said long type bars; the last-mentioned hangers lying below and in overlapping relation to the hangers for the short type bars.

5. In a typewriting machine, the combination of a system of pivoted type-bars, those in the middle of the system being substantially straight from end to end, and the remaining bars having crooks at their free ends, the crooks lying at progressively increasing angles to the bodies of the bars from the middle to the sides of the system, and a plurality of types mounted independently of one another upon each bar, one type mounted upon the tip of the crook, and the other at the junction of the crook with the body of the bar.

6. In a typewriting machine, the combination of a system of pivoted type-bars, those in the middle of the system being substantially straight from end to end, and the remaining bars having crooks at their free ends, the crooks lying at progressively increasing angles to the bodies of the bars from the middle to the sides of the system, and a plurality of types adjustable and detachable independently of one another upon each bar, one type mounted upon the tip of the crook, and the other at the junction of the crook with the body of the bar.

7. In a typewriting machine, a system of pivoted type-bars, those in the middle of the system being substantially straight from end to end, and the remaining bars having crooks at their free ends, the crooks lying at progressively increasing angles to the bodies of the bars from the middle to the sides of the system, each of said bars formed with a type socket at the tip of the crook, and a separate type socket at the junction of the crook with the body of the bar.

8. In a typewriting machine, the combination with a system of type bars and a system of keys, of intervening bell cranks and key-bearing levers, the latter directly engaging said bell cranks at a relatively great leverage, and links extending from said key levers to said bell cranks and attached to the latter at such points as to transmit motion from the key levers to the bell cranks at a relatively small leverage; said links having lost-motion connections to the type-bars so as to

be ineffective during the initial portions of the type-bar strokes.

9. In a typewriting machine, the combination with a system of type bars and a system of keys, or levers operated by the keys, sub-levers between said levers and the type bars, each lever directly engaging its sub-lever at a relatively great leverage, and links extending from the key-levers to the sub-levers to act on the latter at a relatively small leverage, said links having lost-motion connections so as to be ineffective during the initial portions of the type-bar strokes.

10. In a typewriting machine, the combination with a system of type bars and a system of keys, of levers operated by the keys, sub-levers between said levers and the type bars, each lever directly engaging its sub-lever, and links extending from the key-levers to the sub-levers; said links engaging said sub-levers at points between the fulcrums of the latter and said bearings, and having lost-motion connections such that they are ineffective at the initial portions of the type bar strokes.

11. In a front strike writing machine, the combination with a system of rearwardly striking type bars, of levers extending rearwardly beneath the type bars and bearing keys at their forward ends, bell-cranks mounted above the key levers, arms rigid with and extending up from said key levers and directly engaging said bell-cranks, links extending up from said keys levers and having lost-motion connections to said bell-cranks between the fulcrums of the latter and said bearings, and means connecting said bell-cranks to said type bars.

12. In a typewriting machine, the combination with type bars of key-levers bell-cranks connected to the key levers, links ex-

tending from the bell cranks to the type bars, and springs also extending from the bell-cranks and connected to the type bars nearer the pivots of the latter than said links.

13. In a front strike writing machine, the combination with a system of rearwardly striking type bars, of key-bearing levers of the second order extending rearwardly beneath the type-bars, bell-cranks mounted above the key-levers, arms rigid with said key-levers and extending to said bell-cranks and having bearings on the latter forwardly of their fulcrums, links extending up from said key-levers in rear of said arms and having lost-motion connections to said cranks between said bearings and fulcrums, and links extending rearwardly from said bell-cranks to the type bars.

14. In a typewriting machine, the combination with rearwardly striking type bars, of key-bearing levers of the second order beneath said type bars, and bell-cranks having upstanding arms connected to said type-bars; said key-levers having arms rigid therewith and extending upwardly and engaging said forwardly projecting arms of said bell-cranks.

15. In a typewriting machine, the combination with rearwardly striking type bars having pendent short arms, of links extending forwardly from said short arms, bell-cranks having upwardly extending arms connected to said links, and key-bearing levers of the second order having upwardly extending rigid arms which engage forwardly extending arms of said bell-cranks.
